UNITED STATES PATENT OFFICE.

JOSEPH F. SARGENT, OF MELROSE, ASSIGNOR TO ELMER TOWNSEND, OF BOSTON, MASSACHUSETTS.

IMPROVED MACHINE FOR NAILING AND PEGGING BOOTS AND SHOES.

Specification forming part of Letters Patent No. **94,654**, dated September 7, 1869; patented in England November 5, 1868.

To all whom it may concern:

Be it known that I, JOSEPH F. SARGENT, of Melrose, in the county of Middlesex and State of Massachusetts, have invented Improvements in Machines for Nailing and Pegging Boots and Shoes; and I do hereby declare that the following, taken in connection with the drawings which accompany and form part of this specification, is a description of my invention sufficient to enable those skilled in the art to practice it.

The invention relates, particularly, to some of the details of construction of that class of machines for uniting soles of boots and shoes to the uppers in which the fastenings are cut from a continuous screw-threaded wire, though some of the improvements are alike applicable to common pegging-machines in which the pegs are cut from strips or ribbons of wood, (this being particularly the case as relates to the "jack" or shoe-supporting mechanism,) one branch of the invention having particular reference to and consisting in the peculiar construction and arrangement of the jack mechanism, while another part has reference to and consists in the peculiar construction and arrangement of the wire feeding and cutting mechanism.

The drawings represent a machine embodying my improvements.

A shows the machine in front elevation. B is a view of one side of the machine. C is a side view of the opposite side of the head. D is a vertical section on the line *x x*, looking toward the rear of the machine.

a denotes the post for supporting the head *b*, which carries the shoe-feeding, wire-feeding, and wire-cutting mechanism. *c* is the driving-shaft; *d*, the swing-plate at the front of the head, oscillating movement of which plate imparts the intermittent feed-movement to the shoe, to bring it into position to receive successive pegs or nails, the plate being hung on a pin, *e*, and carrying a feed-foot, *f*, and having its lateral or vibratory movement imparted to it by a rocker-lever, *g*, a pin projecting from one arm of the lever into a cam-groove in a cam-wheel, *h*, on the shaft *c*, and a pin projecting from the opposite lever-arm, entering

a slot in the back of the swing-plate, this last pin being adjustable in a vertical slot in the lever-arm; so that by setting it higher or lower the spacing of the nails may be adjusted as may be desirable.

The feed-foot (which may have a roughened surface, or may carry an awl or a feed-tooth) is fixed to the lower end of the bar, which slides vertically in the swing-plate, and vertical movements are imparted to the feed-foot by a cam-groove in a cam-wheel, *i*, on the shaft *c*, acting upon a pin projecting from the slide-bar into the groove.

k denotes the peg-tube foot, this foot containing the tube, into which the end of the wire is fed or transferred, and through which it is forced by the driver *l* into the sole. Instead of making this foot movable, as in other machines, to transfer the contact of the sole from the feed-foot to it, in order that the feed-foot may move back after having fed the shoe, this foot is made stationary, and its lower end acts as a detainer to the shoe, while the feed-foot swings back after having fed forward the shoe, the feed-foot first descending against the shoe, (which, by descent of the foot, is carried away from the detainer or peg-tube foot,) then moving toward and up against the peg-tube foot, carrying the shoe laterally with it, then rising so that its lower end is brought slightly above the detainer-foot, letting the shoe up against the detainer-foot, and leaving the shoe against such foot, (the shoe being pressed up by the weighted jack-lever,) and then swinging back to its normal position, leaving the shoe detained against the peg-tube foot, the construction, arrangement, and operation of this shoe-feeding mechanism (except as regards the stationary peg-tube foot) and the mechanism for actuating the driver being the same, or substantially the same, as may be seen in other pegging-machines made and patented by me, the peg-driver *l* being fastened to a driver-bar, *m*, driven down by a spring, *n*, the bar being lifted by a pin projecting from the cam-wheel *i*, acting upon an arm on the rear face of the bar, and being thrown down by the spring when released from the pin.

The wire being placed on a suitable reel or spool, its end is passed down through a tube made by two grooves in the adjacent faces of the head a and a plate, o , this tube conducting the wire between two feed-wheels, p q , one of which may be a friction-wheel, while the other is fixed upon a shaft, r , to which an intermittent rotative movement is imparted, the peripheries of the wheels being toothed or serrated, and their action upon the wire as the shaft r is rotated causing the wire to be fed down between them. The tube s is inclined, and below the feed-wheels leads into a groove or to a shoulder, t , on a swing-plate or carrier, u , on the end of a rocker-shaft, v , there being just above this carrier a stationary cutter, w , and a movable cutter, x , between which cutters the wire passes from the tube s . The shoulder t , or the groove made thereby between the carrier u and an outer plate, y , terminates at the top of the tube in the peg-tube foot.

The movable cutter x is made circular in form, and reciprocates through the arc of a circle, it being confined by a screw-plate, z , to an arm on the end of a tubular rocker-shaft or quill, a^2 , surrounding the rocker-shaft v . The shaft a^2 runs through the head b , and has on its rear end an arm, b^2 , in which is a slot, c^2 , having an incline, d^2 , between its two straight parts, as seen at D. Through this slot projects a pin, e^2 , from a slide-bar, f^2 , which is moved up and down by an eccentric, g^2 , and link h^2 . The rocker-shaft v , which carries the shoulder-plate u , passes through the cutter-shaft, and has on its rear end an arm, i^2 , having a slot, k^2 , through which the pin e^2 also extends, this slot also having an incline, l^2 , as seen at D.

When the bar f^2 descends, the pin strikes the incline d^2 of the cutter-shaft arm first, and moves up the cutter a little in advance of the movement of the arm i^2 and shoulder-plate or carrier u . The forward rotative movement of the cutter brings its cutting-edge against the wire, pressing the wire against the stationary cutter, and severing the wire at this point. The end thus severed falls against the shoulder t , and as the pin e^2 farther descends it passes into the lower and now vertical part of the slot c^2 , leaving the cutter-shaft at rest, while such farther descent of the pin, acting on the incline l^2 of the arm i^2 , throws forward the carrier-plate u , and brings the wire resting against the shoulder t into upright position, in which position the shoulder of the carrier makes, with a stationary shoulder in the plate y , a vertical tube, from which the severed nail drops down into the stationary tube of the peg-tube foot, the driver being up, bringing it into position to be driven into the shoe by and at the next descent of the driver.

When the bar f^2 rises, the cutter and the carrier-plate are carried back to their normal position, as will be readily understood, for the next feed-movement of the wire, the movement of the feed-shaft r being produced by mechan-

ism, as follows: The shaft r carries a ratchet-wheel, j^2 , with which engages a spring-pawl, x^2 , hung on one arm of a rocker-lever, m^2 , fulcrumed on the shaft r , the end of the other arm being connected to an eccentric, n^2 , on the shaft e by a link, y^2 . As the driver, after driving the nail, next rises the pawl is thrown forward by the eccentric n^2 , imparting rotative movement to the shaft and its feed-wheel, and feeding down the wire to an extent equal to the length of the nail to be driven, the cutter-arm and carrier-plate being drawn back to allow the wire to pass freely by them. The feed-movement of the wire is finished during the first part of the upward movement of the driver, the cutter being thrown forward to cut the wire, and the shoulder-plate forward to transfer the severed nail into the peg-driver tube before the upward movement of the driver is completed, or while the driver is at its highest point.

As the different portions of a sole vary in thickness, it is necessary that the nails correspondingly vary in length, and as the hands of the operator are engaged in guiding the shoe, and as it is desirable that the change from long to short nails and from short to long nails in going into and from the shank should be effected without stopping the machine, it is requisite that provision should be made for effecting change in the extent of rotative movement of the feed-shaft ratchet by the foot of the operator while the nailing operation is progressing.

In Letters Patent No. 77,104, granted to me, a provision is made for producing variable feed of the ratchet-wheel by hand by means of a movable shell partially covering the ratchet-wheel, such shell being moved forward or back under the path of the pawl, so as to cause the pawl to traverse a greater or less extent in contact with the ratchet-teeth. In the present machine, instead of such shell, I use a circular guard, z^2 , whose edge is concentric with the ratchet-teeth, (but projects a little beyond them,) except in a small part, where the edge is cut away or comes below the teeth. The guard plate or disk turns on the feed-shaft, and by rotating it more or less its projecting edge is thrown into the path of movement of the pawl-tooth, this tooth being of a width greater than the thickness of the ratchet, and extending over and resting upon the edge of the guard projecting beyond the ratchet-teeth. The guard is moved by a pin projecting from a crank-arm, o^2 , of a shaft, p^2 , in line with the feed-shaft, and at the outer end of this shaft p^2 is an arm, q^2 , connected by a rod, r^2 , with a treadle or foot-lever, s^2 , so that by tipping the treadle up or down the projecting edge of the guard is thrown more or less into the path of the pawl, thereby causing more or less movement of the ratchet-wheel and a greater or less extent of feed of the wire.

In any specific style of shoes being pegged there is, of course, a uniformity of thickness

of sole in the corresponding parts of different shoes, and as long nails of uniform, or nearly uniform, length are required all along the main sole, and short nails of uniform length are required in the shank, I make the extent of movement of the guard adjustable, so that no nails cut can exceed the required length for the long nails, nor be cut shorter than the nails required in the shank. To effect this, two ears, u^2 , project from the opposite sides of the shaft p^2 , through each of which an adjusting-screw, t^2 , extends, the end of each screw striking against the head a , when the shaft is turned in one or the opposite direction, and thereby stopping further movement of the ratchet-guard in such direction, and determining the greatest length and the shortest length of nails that can be cut from the wire while the machine is in operation, the change from short to long and from long to short nails being instantly or gradually made by the operator during the operation of the machine.

Each wire-cutter is made with a beveled or chisel edge, the lower surface of the cutters being straight to the cutting-edge, and the edge beveling back to the top surface, so that the top of the severed nail is cut square, while the end of the wire above, forming the point of the next nail, is pressed into an awl-point form.

The wire may be cut by two movable cutters, moving toward each other and meeting at the center of the wire, or the one movable cutter may act against a flat-surfaced bed. The swing-carrier which takes the cut nail may be made in one piece with the peg-tube foot, as seen at E, the foot then swinging from inclined to vertical position to bring the tube under the driver; or the carrier may be made in one piece with the plate y , as seen at F, the plate, of course, being then movable, and the wire being fed from the feed-wheels down into a tube running through the swing-piece. The specific construction shown, however, I consider to be the most practical.

The shoe to be nailed is mounted upon a jack mechanism, as follows: a^3 denotes the jack-supporting upright, pivoted to the front end of a weighted lever, b^3 , by a swivel-foot, c^3 , said foot swiveling freely toward and away from the post a upon a pin, d^3 , connecting it to the lever and the upright a^3 , swiveling loosely (upon the pin by which it is hung to the swivel-foot) in a lateral direction, these two movements not only permitting the jack to be moved entirely away from the pegging mechanism to permit a shoe to be placed upon the last or removed therefrom, but also permitting the shoe to be fed by the nailing mechanism, as is required, to bring the whole edge of the shoe to the action of the nail-driver.

To the top of the upright is jointed, by a pin, e^3 , the jack-holder f^3 , this holder hanging pendulously on the pin, and being kept up to the upright by a lip, g^3 , the extent of its vi-

brating movement in either direction being limited by stops j^3 , which stops are made adjustable, so as to regulate the extent of tipping movement to the degree of curvature in the soles or shanks of the style of shoes to be pegged or nailed upon the machine. From the holder projects a spindle, h^3 , upon which the jack O is mounted, a socket-piece, i^3 , on the jack supporting it upon the spindle and permitting free rotative movement of the jack on the spindle. Directly over the spindle the last-holder is hung by a screw, k^3 , this holder having a horizontal bar, l^3 , from which depends an arm, m^3 , having an upright, n^3 , to which is jointed the arm which carries the heel-pin o^3 , this arm projecting down at the side of the bar m^3 , to the top of which it is jointed, and carrying a spring-pawl engaging with the ratchet, outward pressure of the lower end of the arm forcing the last against the toe-piece p^3 , against which it is detained by the pawl and ratchet. The two arms m^3 and n^3 form a handle for one hand of the operator in guiding the shoe being pegged, and another arm, q^3 , projecting down from the other end of the bar l^3 , forms a handle for the other hand. In the arm q^3 is a slot, r^3 , into which projects a pin extending from the end of one arm, s^3 , of a bent lever, fulcrumed at t^3 to an extension, x^3 , from the socket-piece i^3 . To the other arm, u^3 , of this lever is fixed a spring, v^3 , locking into a slot in the edge of a lip, y^3 , on the piece x^3 , locking the shoe in stationary position relatively to the socket-piece.

So far as the relative arrangement of the parts to which the shoe is directly jacked is concerned, the jack mechanism does not materially differ from that shown in my patent No. 44,691. In such patent there is claimed in a pegging-machine "the employment of a jack so constructed or mounted that it can turn or be turned laterally to hold the shoe properly to the action of the awl throughout its varying lateral curvature," and the arrangement now shown is embraced by such claim.

In the specific construction shown in such patent, however, the jack is automatically tipped as the variously curved portions of the edge of the sole come under the action of the shoe-feeding and peg-driving mechanism by a jointed connection with the pegging-machine standard. Such arrangement requires great skill and strength in the operator to keep the shoe firmly in position, and the purpose of my present construction is to not only enable the jack to be freely tipped by the operator, but to cause the shoe to be held steadily in position under the driver. For this purpose I place the pin upon which the jack turns up close to the last, as seen in the drawings, and arrange the jack-holder to be tipped freely by hand, the tipping bar or holder not being a part of the jack itself, but being tipped by the handles of the jack, so that this tipping movement, being independent of the rotating movements of the jack, leaves the jack equally

free to be tipped by hand in all positions into which the shoe is brought under the driver. Then the pin upon which the jack-holder tips is so arranged that when the shank of the sole is pressed up against the feed and peg-tube foot the pressure swings the bottom of the holder up toward the standard, the holder being held by the stop-pin, and the shoe being held firmly in the position into which it is tipped by the pressure between the lever and the pegging mechanism, (a line drawn from the lever-pin to the feed-foot passing outside of the pin on which the jack-holder is hung,) while, as the shoe is fed from the shank toward the toe or heel, the holder is thrown outward as soon as the shoe, in being turned, is brought to such position that a line from the feed-foot to the lever-pin will pass inside of the jack-holder pin, the changing positions thus assumed by the jack being those necessary to keep the surface being pegged in proper position relative to the peg-driver for each nail to enter the sole perpendicularly to the surface into which it is driven. Thus the efforts of the operator may be wholly directed to guiding the shoe without outlay of strength to keep it in position.

The shoes to be nailed are placed upon metal-bottomed lasts, and the blow of the driver not only drives the nail, but upsets one or both ends of the nail, the metal surface of the last acting as an anvil.

I claim—

1. In combination with the wire-feeding and nail-driving mechanism, a cutter having a rotative movement to sever the nail, substan-

tially as described, when the cutter is a separate instrument from the wire-feeding and nail-driving mechanism, and acts to sever the nail before it is driven.

2. In combination with such cutter, an independent vibrating or reciprocating carrier, which receives the end of the wire and transfers it, when cut, from its inclined position to vertical position over the peg-driver tube, substantially as described.

3. In combination with the wire-feed mechanism, a mechanism for enabling the extent of feed of the wire to be varied by the foot of the operator, substantially as described, such mechanism being independent of the shoe-supporting mechanism.

4. In combination with the feed-ratchet, the mechanism for limiting and adjusting the extent of feed-movement of the ratchet, substantially as described.

5. In combination with the shoe-feed foot, having up and down, forward, and back movements, as described, the stationary driver-tube or detainer-foot, substantially as described.

6. The construction and arrangement of the jack-supporting mechanism, by which the shoe may not only be tipped freely by the operator in all directions necessary for its proper presentation, but is held by the stress of the lever-weight toward its proper position, substantially as described.

JOS. F. SARGENT.
